US00D928749S

(12) **United States Design Patent** (10) **Patent No.:** **US D928,749 S**
Jiang (45) **Date of Patent:** **** Aug. 24, 2021**

(54) **VEHICLE MICROPHONE KIT**

(71) Applicant: **Weijun Jiang**, Ningbo (CN)
(72) Inventor: **Weijun Jiang**, Ningbo (CN)
(73) Assignee: **NINGBO KEPO ELECTRONICS CO., LTD.**, Ningbo (CN)

(**) Term: **15 Years**

(21) Appl. No.: **29/706,024**

(22) Filed: **Sep. 17, 2019**
(51) LOC (13) Cl. **14-01**
(52) U.S. Cl. **USPC D14/226**
(58) **Field of Classification Search**

(57) **CLAIM**

The ornamental design for a vehicle microphone kit, as shown and described.

DESCRIPTION

FIG. 1 is a perspective view of the vehicle microphone kit showing the design;

FIG. 2 is a left side view thereof;

FIG. 3 is a right side view thereof;

FIG. 4 is a front elevational view thereof;

FIG. 5 is a rear elevational view thereof;

FIG. 6 is a bottom plan view thereof; and,

FIG. 7 is a top plan view thereof.

The broken lines to the connector in FIGS. 1 and 7 depict environment that forms no part of the claimed design. The cord in FIGS. 1 through 5 is shown with a symbolic break in its length. The appearance of any portion of the cord in between the break lines forms no part of the claimed design.

1 Claim, 4 Drawing Sheets

US D928,749 S
